INVENTOR

MARTHA T. WEAVER.
BY Fisher & Wever ATTYS.

UNITED STATES PATENT OFFICE.

MARTHA T. WEAVER, OF CLEVELAND, OHIO.

TIREFPLACE.

1,010,101.

Specification of Letters Patent. Patented Nov. 28, 1911.

Application filed August 4, 1910. Serial No. 575,484.

To all whom it may concern:

Be it known that I, MARTHA T. WEAVER, citizen of the United States, residing at Cleveland, in the county of Cuyahoga and State of Ohio, have invented certain new and useful Improvements in Fireplaces, of which the following is a specification.

My invention relates to an improvement in fire places, and the invention consists in a fire place having an art patterned and furnished interior and adapted to be lighted or illuminated and heated by electricity, all substantially as shown and described and particularly pointed out in the claims.

In the accompanying drawings, Figure 1 is a front perspective view of my new and original fire place in one of the many possible art patterns or developments of which it is capable with andirons and fire logs in the front of the view. Fig. 2 is a reduced cross section of the fire place and its furnishings intended to show the construction and relation of parts, and Fig. 3 is a vertical sectional elevation of the upper portion 25 of one of the andirons with an electric bulb and a shade mounted on the top thereof.

The invention as thus seen is essentially an embodiment of the artistic with the useful, and is intended to reproduce the enjoyable effects which have ever attended the old fashioned fire place supplemented by the added charm which art alone can contribute to such pleasurable experiences.

To these ends the invention comprises a suitable fire-place or recess built into the wall in any preferred part of a room and which has a depth and height corresponding to fireplaces generally and according to location, size of room and other conditions, the idea of entire harmony with its surroundings being kept in view.

This fireplace need not have a flue or other outlet although one may be provided, and its floor and side walls are built up with or by means of art tiles, porcelain or other artistic material in any preferred style or shade, having in view the other decorations and appointments of the room or apartment as above indicated. Now, with a fire or chimney place or open hearth as thus described, the invention takes an original step beyond all this and all that has heretofore been known or practiced in this art so far as I know or believe, in that it 55 comprises an art developed or decorated background represented by or in what is

shown in the back B of the fire place. This back or rear portion also may be built in with art tiles or tiling or the like in which the picture has a portion of its complete development worked out upon each particular tile, and wherein each tile has its appointed position and relation predetermined by this reason and is finished with such fragmentary surface ornamentation or embellishment as its place in the entire picture may require.

The method of building and using fire-places as heretofore generally practiced has precluded an art patterned, pictured or illuminated back wall for the obvious reason that such a wall would soon become defiled and ruined by smoke and soot arising from coal, wood, gas or other fuel fires. The inventive conception, therefore, could have had no place in or suggestion from previous existing conditions as fire places have been known and used, but with the passing away of the use of burning fuels in open hearths and the substitution of electricity as a heating and lighting or illuminating medium it is found that the heretofore barren and often blackened back wall of a fireplace can be made the subject of the most charming scenic effects and especially when accompanied by the usual artistic fixtures of andirons A, the logs L and the lights glowing therein and shedding their brightness and cheer over the entire scene.

I have stated that the back B in which a coast-wise picture is displayed in natural colors, is preferably built-in with individual tiles, but I do not limit myself to this manner of forming said back or background and it might be produced by frescoing or painting the picture directly upon a back surface, and any preferred picture or scene may be chosen and developed in any preferred way, the present one being merely suggestive or illustrative of what the said back surface may contain.

The andirons A are of special design for my use and the post or standard 2 thereof has a shield or hood 3 of artistic design rotatably mounted on its top and provided with an open inner side. The said standards are shown as tubular and an electric lamp or bulb 4 is supported in the top thereof under cover of said shields 3, so that said lamps will suffuse their light over the decorated field rearward but be entirely concealed as to the front from which observa-

tion is made. Said shield can however be rotated to shed the light into the room when desired for reading or other purposes.

The log L resembles the usual gas log but is an electric log instead. Said log is preferably of metal as it is designed to be conductive of heat and is hollow or has cavities adapted to receive electric heating or resistance coils 5 or any other suitable electric heating device. Lamps or bulbs 6 also are arranged on the rear of said log, say one or more, and a hood or guard 7 on the log extends over said lamps and has the appearance at the front of the fireplace of an additional log relatively above the log L. In this instance the two are cast in one piece. Different or mixed shades or colors of light may be employed according to the effect desired, and of course the candle power can be varied also for different illuminating effects. Different switches should control the said lights and the heating coils. Altogether there is much greater comfort and enjoyment believed to be possible by this modern old time fire-place than by the real ones of old as there is no chimney to draw the heat away, no excessive heating on one side and chilling on the other in cold weather nor brilliant light or heat in the eyes and none of the extremes experienced with log fires while there is draft enough under the log to throw all the heat into the room and thus produce a healthful circulation of the air, but above all a picture of ease and contentment is produced that is exceedingly enjoyable and restful to all the senses.

The electric bulbs 6 are seated in suitable sockets in the rear base flange 10 of the log

L, and the bulb shaped hood 3 of the andiron is preferably provided with a rotatable screen or slide 12 on its interior which may be drawn down, more or less, to cut off the light through the opening 8 in the hood.

With my invention, the direct rays of light from the lamps are shaded from the eye and only a reflected light is thrown forward from the art patterning or picture on the rear wall. The rear wall can thus be utilized to radiate the light into the room in the most pleasing manner and with thousandfold effects, all depending upon the art or color scheme employed. Heretofore, this has been impossible or never before done in so far as I am aware.

What I claim is:

1. As a new article of manufacture and sale, an imitation log for fire places having a rearward substantially hood-shaped top extension of substantially segmental pattern in cross section provided with a roughened log-like front surface and adapted to receive a light relatively behind and beneath the same.

2. A fire place comprising an opaque hollow log having a substantially hood shaped upward and rearward extension lengthwise along its top, in combination with illuminating means located behind the body of said log and relatively beneath said hood-shaped extension.

In testimony whereof I affix my signature in the presence of two witnesses.

MARTHA T. WEAVER.
